OLFACTORY TESTING DEVICE

Charles M. Saffer, Jr., Levittown, Pa., and Oscar W. Felcan, Brooklyn, N.Y., assignors to Witco Chemical Corporation, New York, N.Y.

Filed Oct. 2, 1972, Ser. No. 294,144

Term of patent 14 years

Int. Cl. D24—02

U.S. Cl. D83—1 N

FIG. 1 is a perspective view of an olfactory testing device embodying my new design;

FIG. 2 is a bottom plan view thereof; and

FIG. 3 is a top plan view.

We claim:

The ornamental design for an olfactory testing device, substantially as shown and described.
